VALVE.

Application filed September 6, 1918. Serial No. 252,981.

To all whom it may concern:

Be it known that I, CHARLES F. PECKHAM, a citizen of the United States, residing at Providence, in the county of Providence and State of Rhode Island, have invented certain new and useful Improvements in Valves; and I do hereby declare the following to be a full, clear, and exact description of the invention, such as will enable others skilled in the art to which it appertains to make and use the same.

This invention relates to a valve and more particularly to a valve for controlling the emission of a fluid from an orifice adapted to be retained in a position to close the orifice by external pressure and to be opened by the fluid pressure when a predetermined difference between the fluid and external pressures is reached.

20 The object of the invention is to produce an improved construction of valve of the character indicated adapted to open quickly and positively when the requisite pressure difference is attained and to eliminate the 25 objectionable chattering of previous constructions of valves of the general type indicated.

To this end the improved valve comprises a valve body for closing the orifice. The 30 valve body is provided with a projection of a width slightly smaller than the width of the orifice and arranged to extend sufficiently into the orifice so that during the initial opening movements of the valve the 35 fluid is caused to pass through an initial constricted opening between the projection and the walls of the orifice and to suffer thereby sufficient loss of head so that as the fluid flows under the body portion of the 40 valve little or no additional loss of head takes place so that the development of a region of low pressure under the valve body is prevented. When, therefore, sufficient 45 difference is attained between the fluid pressure and the external pressure to overcome the weight of the valve, the valve will open quickly and positively and without any tendency to pass into a position of balance or to chatter, as has been experienced with 50 previous constructions of such valves.

Referring to the drawing illustrating the preferred embodiment of the invention, Figure 1 is a central vertical section of the valve; Fig. 2 is a front elevation of the 55 same with portions broken away; Fig. 3

illustrates diagrammatically the position of balance assumed by a disk valve of the ordinary type, when the thrust of the static pressure of the fluid has been reduced by the lateral flow of the fluid under the valve, and 60 Fig. 4 illustrates diagrammatically the relation to the orifice of a valve embodying the present invention.

Prior to the present invention the opening of valves of the character and construction of the present valve has been attended by a peculiar phenomenon. It has been found that when the pressure which normally holds the valve to its seat, is reduced and the valve starts to open under the influence of the thrust of the static head of fluid against the inner surface thereof, that the valve moves away from the seat only a short distance into a position of balance. 70 As the valve is moved away from its seat, 75 the effect of the thrust of the static head of fluid upon the valve is diminished by the flow of fluid over the seat and under the marginal portions of the valve, and further movement of the valve is soon arrested because of the equalizing of the opposing pressures on both sides thereof. It is recognized that when the fluid flows in this manner a region of low pressure develops between the fluid and the marginal portions 80 of the under side of the valve with the result that the effective thrust upon the valve tending to open it is greatly reduced. With a certain size of orifice and width of valve, it is possible for the effect of the thrust upon 85 the valve due to the static head of the fluid to be entirely eliminated or at least greatly diminished. In such cases, unless the pressure exerted upon the outer side of the valve has dropped to a negligible quantity, it is 90 obvious that the valve will return toward its seat under the influence of whatever pressure remains upon the outer side thereof. After the valve has returned toward its seat, 95 it is again opened and the above described 100 movements repeatedly occur until the external pressure upon the valve has decreased to a point where the effect of the static head is sufficient to cause the valve to open completely. This phenomenon is commonly referred to as the chattering of the valve. In any event, whether the chattering takes place or not, it is obvious that with previous valves of this type the flow of fluid under the valve decreases the effect of the 110

thrust of the static head of fluid upon the valve, and consequently decreases the speed at which the valve opens, all of which detract from the successful operation of the 5 valve.

Referring to the drawing, the invention is illustrated as embodied in an automatic "dry-pipe" fire-sprinkler system. The valve casing 1 contains a supply chamber 2 and a 10 delivery chamber 3. The supply chamber 2 and the delivery chamber 3 are provided with flanges 4 and 5, respectively, for connecting the chambers with supply and distribution pipes. The valve casing 1 is constructed in two sections suitably secured together by bolts 6, and is formed with a partition plate 7 of bronze or other non-corrosive material, separating the supply and delivery chambers. The partition 7 is provided with an opening or orifice 12 through 15 which the fluid flows when the valve is open, from the supply chamber 2 to the delivery chamber 3 and to the distribution pipes. A cylindrical ring 8 is threaded into the orifice 12 and forms a seat 9 for the valve 11. A gasket 10 of rubber or other suitable material is secured to the valve and is adapted to form a water-tight joint by co-operation with the seat 9. The valve 11 is provided with a cylindrical projection 20 20 secured thereto by a bolt 21 and extended into the orifice 12. The diameter of the cylindrical projection 20 is somewhat less than the diameter of the orifice, whereby 25 a passage 22 is formed between the projection 20 and the interior of the orifice. This passage 22 is normally closed by the gasket 10 resting upon the seat 9. The valve 11 is provided with a flexible ring 13 secured 30 to the marginal portions thereof which seats upon a beveled valve seat 14 concentric with and located somewhat behind the plane of the valve seat 9. A recess 15 is formed when the valve is closed between the marginal 35 portion of the valve and the partition 7.

In operation the valve 11 is held in its closed position by air pressure in the delivery chamber 3 of sufficient amount acting upon the enlarged surface exposed thereto, 40 to counteract the fluid pressure in the supply chamber 2 upon the projection 20 and the portion of the valve closing the passage 22. Fluid-tight joints are maintained between the gasket 10 and valve seat 9 and also 45 between the flexible ring 13 and valve seat 14.

When the air pressure in the delivery chamber 3 is reduced, as for example, when a sprinkler head opens, to such a point that its effect upon the enlarged surface of the 50 valve 11 is insufficient to counteract the effect of the thrust of the pressure of the fluid upon the valve acting upon the projection 20, the valve will start to open. As the valve opens and moves from its seat the effect of the thrust of the pressure within the 55

chamber 2 is exerted upon the projection 20 until the valve has moved away from its seat 9 to such an extent that the flow of fluid over the seat will have no effect upon further movements of the valve. The length of the 60 projection 20 is such that the effect of the thrust of the static pressure of the fluid is maintained during the opening movement of the valve, and until the valve is completely opened. It is therefore, apparent 65 that the valve will open quickly and positively once the pressure of the air within the chamber 3 has been reduced to a point such as to unbalance the opposing thrusts. After the valve has been opened and has 70 moved away from its seat under the impulse of the static head of the fluid in the chamber 2, it falls by its own weight into the position indicated in dotted lines, Fig. 1, so that the force of the fluid flowing out of the orifice 75 12 will not operate to move the valve and, on the contrary, will operate to hold it at the bottom of the chamber and against the inclined wall 23 of the delivery chamber. The flow of fluid is now entirely unobstructed and there is no possibility of the 80 valve becoming columned. When it is desired to replace the valve and to restore the system to its normal operating condition, a 85 plate 25 may be removed and the hand inserted through the hole 24. The delivery chamber 3 is provided with a drain opening 26 which is normally closed by a plug 90 through which water may be drained from the delivery chamber if necessary. 95

The projection 20 also serves to assist the opening movement of the valve, in that the flow of fluid on all sides of the projection operates to maintain the projection in a central position within the orifice 12 so that the valve 11 is moved bodily outward until the projection has substantially left the orifice. Tendencies of the valve to bend or 100 jam are eliminated by the forces set up by the flow of the water on all sides of the projection. 105

An important feature of the invention resides in the provision of means for causing the fluid within the orifice to pass through a constricted opening positioned 110 within the orifice itself and to thereby suffer such loss of head that when the fluid flows under the valve body little or no further reduction in pressure head takes place, thereby eliminating and preventing the formation of a region of low pressure under the valve so that when the requisite pressure difference is attained the static thrust of the fluid operates to cause the valve to open quickly and positively. After the 115 fluid passes through the initial constricted opening between the plunger and walls of the orifice, it flows through a cylindro-anulus formed between the lateral surface of the projection and the walls of the orifice, 120 125 130

thereby suffering additional loss of pressure head by hydraulic friction.

The plunger 20 is cast of bronze or other noncorrosive material and its length or size will of course vary with the size of the orifice. For best results, I have found that the width of the passage 22 between the projection 20 and orifice should not exceed 0.07 of the radius of the supply chamber and that the length of the projection should not be less than eight times the width of this space. The annular opening thus formed permits diminished flow of fluid over the valve seat and under the marginal portion of the valve during the initial portion of its opening movement. The portion of the projection 20 adjacent the valve 11 is hollow and the opposite solid end is of sufficient weight to bring the center of gravity of the entire valve and projection well toward the supply chamber side of the valve so as to facilitate the seating of the valve and to aid in retaining it in position when there is an absence of pressure in the air chamber, during the reseating of the valve.

While the invention has been illustrated as embodied in a "dry-pipe" sprinkler system, it will be understood that it may be embodied in other systems and in other forms of valves in which the valve body is held to its seat by any sort of pressure and moved from its seat by the fluid pressure when a difference between the fluid and external pressures is attained.

Having thus described the invention, what is claimed is:

1. A valve adapted to control the emission of a fluid from an orifice having, in combination, a valve seat surrounding the orifice, a valve body adapted to be retained in a position to close the orifice by external pressure and to be moved from its seat by fluid pressure when a predetermined difference between the fluid and external pressures is attained, and a projection on the valve body extended into the orifice, the projection forming with the walls of the orifice a constricted passage through which the fluid is caused to flow as the valve starts to open and to thereby suffer sufficient loss of head so that the formation of a region of low pressure under the valve is prevented during the opening of the valve.

2. A valve adapted to control the emission of a fluid from an orifice having, in combination, a valve seat surrounding the orifice, a valve body adapted to be retained in a position to close the orifice by external pressure and to be moved from its seat by fluid pressure when a predetermined difference between the fluid and external pressures is attained, and a projection on said valve body extended into the orifice, the projection forming with the walls of the orifice a cylindro-annulus of such size that as the fluid is

caused to flow therethrough during the opening of the valve sufficient reduction in head as to prevent formation of a region of low pressure under the valve during its opening movements takes place.

3. A valve adapted to control the emission of a fluid from an orifice having, in combination, a valve seat surrounding the orifice, a valve body adapted to be retained in a position to close the orifice by external pressure and to be moved from its seat by fluid pressure when a predetermined difference between the fluid and external pressures is attained, and means secured to the valve for forming an initial constricted opening located within the orifice and through which fluid is caused to pass and to suffer a reduction in head whereby the development of a region of low pressure under the valve during its opening movements is prevented.

4. A valve having, in combination, a valve casing provided with supply and delivery chambers and a passage connecting said chambers, an annular valve seat at the delivery end of said passage, a valve body normally held against said valve seat, a projection on the valve body extended into the passage of a size and shape arranged to form with the walls of the passage a constricted opening located within the passage through which the fluid is caused to flow and to suffer sufficient loss of head so as to prevent the formation of a region of low pressure under the valve during its opening movements, a second annular valve seat for the marginal portion of said valve body spaced outwardly from the first mentioned valve seat and a recessed portion of the valve casing between said valve seats forming a chamber normally closed by said valve body and having means for removing or draining off any excess fluid that may leak past the valve seats.

5. A valve having, in combination, a casing provided with supply and delivery chambers, a wall separating said chambers having a passage therethrough, an annular valve seat adjacent the delivery end of said passage and projecting from the plane of the adjacent surface of the casing, a second annular valve seat on said casing separated from the first valve seat, a valve body adapted to be normally held against said seats to close said passage and the space between said seats, and means on said valve body for forming an initial constricted opening within the passage through which the fluid is caused to flow and to suffer sufficient loss of head so that the formation of a region of low pressure under the valve during its opening movements is prevented.

6. A valve having, in combination, a casing provided with supply and delivery chambers, a wall separating said chambers

and having a passage therethrough, an annular valve seat adjacent the delivery end of said passage, and projecting beyond the plane of the adjacent surface of the casing, a 5 second annular valve seat on said casing, surrounding and separated from the first valve seat, and projecting a less distance beyond said adjacent surface, a dish shaped valve body having a recessed portion 10 adapted to be normally held against the first valve seat and a marginal portion adapted to be normally held against the second valve seat and a projection on said recessed portion of a size and shape arranged to form an 15 initial constricted opening within the passage through which the fluid is caused to flow and to suffer sufficient loss of head so that the formation of a region of low pressure under the valve during its opening 20 movements is prevented.

7. A valve having, in combination, a valve casing provided with supply and delivery chambers, a wall separating said chambers and having an opening therein, a cylindrical 25 ring inserted in said opening and projecting into said supply and delivery chambers, an annular valve seat at the delivery end of said ring, a second annular valve seat on said casing, a dish shaped valve body normally held against said seats to close the 30 opening and means on said valve body for forming an initial constricted opening within the passage through which the fluid is caused to flow and to suffer sufficient loss 35 of head so that the formation of a region of low pressure under the valve during its opening movements is prevented.

8. A valve having, in combination, an orifice, a valve body normally held in a position 40 to close the orifice by a constant pressure and adapted to be opened by change in the relative pressures within and without the orifice, and means for forming an initial constricted opening within the orifice and 45 through which the fluid is caused to flow to suffer sufficient loss of head so that the development of a region of low pressure under

the valve during its opening movements is prevented.

9. A differential valve for use in a "dry- 50 pipe" sprinkler system having, in combination, a casing provided with supply and delivery chambers, a wall separating said chambers having a passage therethrough, an annular valve seat adjacent the delivery end 55 of said passage, a valve body normally held in position to close said passage by a relatively light air pressure, and means carried by the valve body and extended within said passage for forming an initial constricted opening within the passage and through which the water is caused to flow to thereby suffer sufficient loss of head to prevent the development of a region of low pressure under the valve body during its opening movements. 60 65

10. A differential valve for use in a "dry- pipe" sprinkler system having, in combination, a casing provided with supply and delivery 70 chambers, a wall separating said chambers having a passage therethrough, an annular valve seat adjacent the delivery end of said passage, a valve body normally held in position to close said passage by a relatively light air pressure, and a projection 75 upon the valve body extended into the opening of such size and shape as to form an initial constricted opening within the passage and through which the water is caused to flow to thereby suffer sufficient loss of 80 head to prevent the development of a region of low pressure under the valve body during its opening movements. 85

11. A valve having, in combination, a valve seat, surrounding an orifice, a valve body for closing the orifice, said valve body being provided with a cylindrical projection extended into the orifice, the portion of the projection adjacent the valve body being hollow, whereby the center of gravity of the 90 valve body and projection, is positioned adjacent the end of the projection. 95

CHARLES F. PECKHAM.
